CARD INDEX

Wentworth H. Shortridge, West View, Pa.

Application November 23, 1932, Serial No. 643,982

19 Claims. (Cl. 129—16)

In my invention the cards are mounted on the support, which is usually in the form of a tray and for convenience is hereinafter referred to as such, by means of a novel form of carrier bar which is mounted in the tray in a novel manner so that an individual bar and the card or cards mounted on the bar may be conveniently offset relative to the cards on the remaining bars and may be returned to their normal or aligned position without removing the bar from the tray. The bar may also be conveniently inserted in or removed from the tray at any point without disturbing the remaining bars and also without dismounting the card or cards from the bar which is to be inserted or removed.

I use the term cards herein as inclusive of sheets of paper, such for instance as correspondence and the like.

I also provide new and improved means for mounting the cards on the carrier bars, one or a plurality of cards being mounted on the individual bars and a card being mounted on or dismounted from a bar without disturbing the card or cards on the same bar.

I also provide means for locking the card or cards to the carrier bar to prevent their accidental dislodgment therefrom.

Other novel features of construction and also of arrangement of parts will appear from the following description.

In the accompanying drawing wherein I have illustrated a practical embodiment of the principles of my invention, Fig. 1 is a broken plan view showing a series of index cards and carrier bars mounted on a tray, one of the cards being shown offset.

Fig. 2 is a sectional view taken along the line 2—2 in Fig. 1.

Fig. 3 is a cross-sectional view on enlarged scale taken along the line 3—3 in Fig. 1, the carrier bar being shown in its normal or aligned position.

Fig. 4 is a longitudinal section of one of the carrier bars.

Fig. 5 is a top plan view of one of the carrier bars.

Fig. 6 is a view similar to Fig. 3 but showing the bar offset.

Fig. 7 is a detail in section showing a plurality of cards mounted on the same carrier bar, the bar being in section along the line 7—7 in Fig. 5.

Fig. 8 is a broken face view of one of the cards.

Fig. 9 is an end view of the same.

Fig. 10 is a plan view of a modified form of

carrier bar arranged to receive cards of different dimensions.

Fig. 11 shows another modified form of carrier bar arranged for mounting a large group of cards thereon.

Fig. 12 is an enlarged perspective of the filler clip which may be used to keep the cards snugly in position on the carrier illustrated in Fig. 11.

Referring first to Figs. 1 to 9 inclusive, 1 represents the tray which preferably has a continuous bottom. The tray may be conveniently made of metal and its lateral edges are flanged upwardly, defining its sides.

Thus at one side, the left side in the drawing, the metal is first flanged upwardly as at 2 and then doubled downwardly as at 3, and then bent horizontally and inwardly to form a lip 4 which is spaced slightly above the bottom of the tray so that the ends of the carrier bars may be inserted therein, as will later appear.

At the other side of the tray the metal is first flanged upwardly as at 5, then doubled inwardly and downwardly as at 6 and then flanged horizontally in flat contact with the bottom of the tray as at 7 with its inner end turned upwardly to form a low vertical rib 8.

9 is a spring-metal tongue extending inwardly and downwardly from the side of the tray. The same may be riveted or otherwise secured to the portion 6.

The ends of the tray 1 may be flanged upwardly as at 1a.

10 represents the carrier bars which preferably are formed of sheet-metal, such as aluminum. If desired the carrier bars may be made of wood, 35 stiff and substantial paper or other suitable material. The bars are preferably of the inverted trough form shown and the ends of the bars are formed by the tongues 11 and 12 respectively, which incline downwardly to the bottom level as shown, so that they may be inserted beneath the lip 4 and the spring tongue 9, respectively. Adjacent to its ends the trough body is pinched in laterally as at 13, to strengthen and stiffen the bar.

14 represents longitudinally elongated openings cut in the top wall of the bar adjacent the ends of its trough portion, and 15 represents slideable shutters arranged to contract the length of the openings 14 from their inner or adjacent ends, 50 the shutters being held in position against the under side of the bar by the screws 16 which extend through slots in the bar.

Adjacent to the end of the bar which engages the spring tongue 9 the side walls of the bar are 55

cut from below to form the two spaced apart and opposed abutments 18 and 19 and the intervening depending shoulder 20 which preferably stops short of the lower edge of the bar.

5 When the bar is mounted on the tray it may be positioned with either abutment 18 or 19 bearing against the rib 8. Thus when the abutment 18 abuts inwardly against the rib 8 as shown in Fig. 3, the bar and the card or cards carried thereby are in their normal or alined position, but when as shown in Fig. 6 the abutment 19 bears outwardly against the rib 8, the card or cards mounted on the bar are offset, as is the case of the card in Fig. 1 which bears the name "Alter".
 10 15 A card may be moved from its normal position to its offset position by moving the bar longitudinally from left to right, and a card may be returned to its alined position by moving the bar from right to left. The shoulder 20 interposed 20 between the abutments 18 and 19 prevents accidental shifting of the bar and its card or cards, owing to the pressure on the bar exerted by the spring tongue 9.

The bars are of such length that by moving 25 the bar farther to the left from its position shown in Fig. 3, the right end of the bar is moved from under the tongue 9 and the bar and its card or cards may then be lifted from the tray. In mounting the bar on the tray, the left end of 30 the bar is first inserted under the lip 4 far enough to permit the other end of the bar to clear the spring tongue 9 and then the bar is moved to the right until its right end is inserted under said tongue. In moving the bar longitudinally in 35 either direction, as above described, the resiliency of the tongue 9 permits the bar to be raised sufficiently for the abutments and intervening shoulder to clear the rib 8.

Again, the carrier bars may be made long 40 enough to prevent the right end moving out from under the tongue 9 when moved to the extreme left. In such case the tongue 9 is sprung upwardly to permit the end of the bar to clear the tongue in installing or removing the bar.

45 The cards illustrated at 21 are of any convenient size and proportions, depending upon the capacity of the tray and the carrier bars, and are flexible. 22 represents the hinge members which are attached to the lower edges of the cards and 50 which may be of any suitable material. I prefer however to use kraft paper or linen to prevent tearing. Preferably such hinge members are of inverted T-shape with their inverted stems split or double as at 23, so that the card may be inserted down between the leaves and secured thereto as by pasting or riveting. The horizontal portions or heads 24 of the hinge members are spaced below the edge of the card and are disposed horizontally.

60 Where the card is flexible the hinge members may be so placed that by flexing the card the heads of the hinge members may be inserted in the openings 14 and when the card is allowed to straighten the outer ends of the heads move outwardly past the outer ends of the openings, thus 65 hingedly securing the card to the bar. The card may be conveniently removed from the bar by again flexing the card to withdraw the horizontal portions of the hinges into the openings in the bar.

70 The openings 14 in the bar are preferably made wide enough to receive the hinges of a plurality of cards, as illustrated in Fig. 7, and it is evident that any individual card may be mounted 75 on or dismounted from a bar without disturbing

the other cards mounted on the bar. It is further evident that the card or cards may be mounted on or dismounted from a bar without removing the bar from the tray.

5 After the card or cards have been mounted on the bar, the shutters 15 may be advanced sufficiently to contract the openings 14 so that the cards cannot be flexed or moved relative to the bar and thus disengaged from the bar unless the shutters are first retracted.

10 Where the card is not flexible, its hinge members may be inserted into the openings of the bar and the card then shifted, usually toward the left so that the heads of the hinge members engage beneath the left end of the openings 14. The 15 shutter 15 of the left opening may then be adjusted to contract the opening and prevent accidental release of the card from the carrier bar. This method may also be advantageously used in case the card is a sheet of relatively thin paper 20 such as correspondence paper.

15 If desired but one hinge member may be used and the shutter employed to lock it in the proper opening in the bar, but I prefer to employ two hinge members for each card. If desired the 25 hinge members may be L-shaped—that is with the head extending to one side only, but I prefer the inverted T-shaped type.

20 In Fig. 10 I show a carrier bar 19a arranged for cards of different dimensions. Thus three 30 sizes of cards may be accommodated, such as index cards, which are in common use, eight by five inches; six by four inches, and five by three inches, and it is advantageous to provide for the simultaneous mounting of two or more sizes of 35 cards on the same carrier bar.

25 Thus the bar is provided with the usual left-hand opening 14a and adjacent to its other end with three spaced openings 14b, 14c and 14d. The hinge members of the largest size card are 40 inserted in openings 14a and 14d; those of the intermediate size card in openings 14a and 14c, while those of the smallest card in openings 14a and 14b. The opening 14a is provided with a shutter which is shifted to lock the hinge members of the cards in the opening 14a.

30 In Fig. 11 I have shown a bar 19b having a body or trough portion of increased width to provide additional width for its openings 14. Thus a 45 relatively large group of cards may be mounted 50 on the same bar.

To hold the cards in proper position when less than the bar-capacity of cards is mounted on the bar, I provide means for adjusting the effective width of the openings to suit the number of cards 55 actually mounted on the bar. Thus I may provide the spring spacer bar 25 having curved flanged ends or toes 26 which may be sprung into the openings 14 and engage the ends of the openings. The spacer clip may be slid into proper 60 position to hold the cards in place with the requisite snugness. Again by sliding the spacer clip the openings in the carrier bars may be enlarged as additional cards are mounted on the carrier bars or reduced as cards are removed.

65 The following are some of the numerous advantages of my improved card file.

Any one or more of the cards may be quickly and conveniently offset and returned to normal alignment without disturbing the remaining 70 cards in the file.

75 Any size and number of cards or other papers may be mounted on a carrier bar within the limits of the width of the tray and within the capacity of the hinge-openings in the carrier bar.

Carrier bars of any desired card-capacity may be employed and the capacity of the individual bars adjusted so that any number of cards within the limit may be held snugly in position.

5 By means of the shutters a card or cards may be conveniently locked against accidental dismounting. This is particularly advantageous as the cards may be of very thin or flexible material, or even thin sheets of paper, such as correspondence, which would easily flex and thus, unless some locking means were provided, the card or sheets would tend to release themselves when handled.

10 Where a plurality or group of cards are mounted on a single carrier bar, any one or more of them may be removed without disturbing the remaining cards on the bar, and additional cards may be added to the group and mounted on the same bar without disturbing those already 15 mounted thereon, and these added cards may be interposed as desired between the already mounted cards.

15 While I prefer to use metal as a material for the carrier bars, wood, substantial paper or other material may be used.

20 I claim:—

1. In a card file, the combination of a support, a carrier bar arranged to be detachably and slidably mounted on the support, said bar being provided with spaced-apart openings, a card having hook-shaped hinge-members depending from its edge, said card being adapted to be mounted on the bar by inserting the free ends of the hinge-members into the openings and then moving said hinge-members to hook them under the edges of the openings, and means for preventing the accidental disengagement of the hinge-members from the openings.

25 2. In a card file, the combination of a support, a carrier bar arranged to be detachably and slidably mounted on the support, said bar being provided with spaced apart openings, a card having hook-shaped hinge-members depending from its edge having their free ends extending toward the opposite ends of the card, the card being adapted to be mounted on the bar by flexing the card to permit the insertion of the hinge-members through said openings and the free ends of the hinge-members moving past the outer ends of the openings when the card straightens, the card straightens to hook under the edges of the openings, and means for preventing the accidental disengagement of the hinge-members from the openings.

30 3. In a card file, the combination of a support, a carrier bar arranged to be detachably and slidably mounted on the support, said bar being provided with spaced apart openings, a card having hook-shaped hinge-members depending from its edge, said card being adapted to be mounted on the bar by inserting the hinge-members into the openings and moving the hinge-members to hook the hinge-members under the edges of the openings, and means movably mounted on the bar to restrict said openings and prevent the accidental disengagement of the hinge-members therefrom.

35 4. In a card file, the combination of a support, a carrier bar arranged to be detachably and slidably mounted on the support, said bar being provided with spaced apart openings, and a card having hook-shaped hinge-members depending from its edge, said card being adapted to be mounted on the bar by inserting the hinge-members into said openings and then moving the

hinge-members to hook them under the edges of the openings, the openings in said carrier bar being of sufficient width to accommodate the hinge-members of a plurality of cards arranged in parallelism.

5. In a card file, the combination of a support, a carrier bar arranged to be detachably and slidably mounted on the support, said bar being provided with spaced apart openings, and a card having hook-shaped hinge-members depending from its edge having free ends extending toward the opposite ends of the card, the card being adapted to be mounted on the bar by flexing the card to permit the insertion of the hinge-members through said openings and the free ends of the hinge-members moving past the outer ends of the openings when the card straightens, the openings in said carrier bar being of sufficient width to accommodate the hinge-members of a plurality of cards arranged in parallelism.

10 6. In a card file, the combination of a support, a carrier bar arranged to be detachably and slidably mounted on the support, said bar being provided with spaced apart openings, a card having hook-shaped hinge-members depending from its edge, said card being adapted to be mounted on the bar by inserting the hinge-members into said openings and then moving the hinge-members to hook them under the edges of said openings, the openings in said carrier bar being of sufficient width to accommodate the hinge-members of a plurality of cards arranged in parallelism, and means for adjustably limiting the effective width of said openings to hold the cards in proper relation.

15 7. In a card file, the combination of a support, a carrier bar arranged to be detachably and slidably mounted on the support, said bar being provided with spaced apart openings, a card having hook-shaped hinge-members depending from its edge having their free ends extending toward the opposite ends of the card, the card being adapted to be mounted on the bar by flexing the card to permit the insertion of the hinge-members through said openings and the free ends of the hinge-members moving past the outer ends of the openings when the card straightens, the openings in said carrier bar being of sufficient width to accommodate the hinge-members of a plurality of cards arranged in parallelism, and means for adjustably limiting the effective width of said openings to hold the card in proper relation.

20 8. In a card file, the combination with a support provided along one edge with an overlying flange and at its opposite edge with a spring tongue, and a card-carrier bar arranged to be mounted on said support, said bar being of such length as to be installed in said support by first having its one end inserted under said flange with its other end clearing said tongue and then moved longitudinally to engage the last mentioned end under said tongue, the spring tongue being arranged to bear downwardly on the bar to prevent accidental longitudinal movement of the latter whereby the bar may be shifted longitudinally relative to the support to adjust its position and the bar is held in its adjusted position against accidental movement therefrom.

25 9. In a card file, the combination of a support provided at one edge with an overlying flange and at its opposite edge with an overlying spring tongue, said support being provided with a rib parallel to said tongue, and a card-carrier bar having its ends arranged for insertion under said

- flange and tongue, the bar being provided with an abutment arranged to bear against said rib to prevent accidental longitudinal movement of the bar.
- 5 10. In a card file, the combination of a support provided at one edge with an overlying flange and at its opposite edge with an overlying spring tongue, said support being provided with a rib paralleling said tongue, and a card-carrier bar 10 having its ends arranged for insertion under said flange and tongue, the bar being provided with opposed and spaced apart abutments, one abutment bearing on the rib when the bar is in one of its positions and the other abutment bearing 15 against said rib when the bar is in the other of its positions, the spring tongue preventing the accidental shifting of the bar out of either of its positions.
11. In a card file, the combination of a support 20 provided at one edge with an overlying flange and at its opposite edge with an overlying spring tongue, said support being provided with a rib paralleling said tongue, a card-carrier bar having its ends arranged for insertion under said flange 25 and tongue, the bar being provided with opposed and spaced apart abutments, one abutment bearing on the rib when the bar is in one of its positions and the other abutment bearing against 30 said rib when the bar is in the other of its positions, and a shoulder interposed between said abutments, whereby the spring tongue prevents the accidental shifting of the bar out of either of its positions.
12. In a card file, the combination of a support, 35 a carrier bar arranged to be mounted on the support, said bar being provided with an opening adjacent one end thereof, and a plurality of spaced apart openings adjacent the other end of the bar, and a plurality of cards of different dimensions, said cards being provided with depending angular hinge-members arranged to be inserted in the proper openings, said hinge-members being adapted to be moved to hook them under the edges of said openings.
13. In a card file, the combination of a support, 40 a carrier bar arranged to be mounted on the support, said bar being provided with an opening adjacent one end thereof, a plurality of spaced apart openings adjacent the other end of the bar, and a plurality of cards of different dimensions, said cards being provided with depending angular hinge members arranged to be inserted in the proper openings, said hinge members being adapted to be moved to hook them under the edges of said openings, and means for preventing the accidental disengagement of said hinge members from said bar.
14. In a card file, the combination with a support, 45 a carrier bar arranged to be detachably mounted on said support, said bar being provided with a top wall elevated above said support and said wall being provided with an opening and a card to be detachably mounted on the bar, a hook-shaped member depending from the card and having a horizontal portion arranged to be inserted downwardly through the opening in the bar and moved laterally to engage underneath the top wall of the bar, of means carried by the bar for preventing the disengagement 50 of the member from the bar by the accidental longitudinal shifting of the card.
15. In a card file, the combination with a support, 55 a carrier bar arranged to be detachably mounted on said support, said bar being provided with a top wall elevated above said support and said wall being provided with an opening and a card to be detachably mounted on the bar, a hook-shaped member depending from the card and having a horizontal portion arranged to be inserted downwardly through the opening in the bar and moved laterally to engage underneath the top wall of the bar, of means carried by the bar for reducing the capacity of said opening to prevent the accidental disengagement of the card from the bar.
16. In a card index, the combination of a support 60 provided with a bottom and an overhanging lip and spaced therefrom an overhanging spring tongue, and a carrier-bar provided with means for attaching a card thereto and having its opposite ends arranged to engage under the lip and tongue, the spring tongue pressing down on the inserted end of the bar to prevent accidental longitudinal movement of the bar relative to the support.
17. In a card index, the combination of a support 65 provided with a bottom and an overhanging lip and spaced therefrom an overhanging spring tongue, and a carrier-bar provided with means for attaching a card thereto and having its opposite ends arranged to engage under the lip and tongue, the spring tongue pressing down on the inserted end of the bar to prevent accidental longitudinal movement of the bar relative to the support, said bar being of the proper length so that it may be detachably mounted on the support by first inserting one end under the lip sufficiently to permit the other end of the bar to clear the spring tongue and then moving the bar longitudinally to engage its last named end under the spring tongue.
18. In a card index, the combination of a support 70 provided with a bottom and an overhanging lip and spaced therefrom an overhanging spring tongue, and a carrier-bar provided with means for attaching a card thereto and having its opposite ends arranged to engage under the lip and tongue, the spring tongue pressing down on the inserted end of the bar to prevent accidental longitudinal movement of the bar relative to the support, the end of the bar being flattened to prevent rotation of the bar on its longitudinal axis.
19. In a card index, the combination of a support 75 provided with a bottom and an overhanging lip and spaced therefrom, an overhanging spring tongue, and a carrier-bar provided with means for attaching a card thereto and having its opposite ends arranged to engage under the lip and tongue, the spring tongue pressing down on the inserted end of the bar to prevent accidental longitudinal movement of the bar relative to the support, the end of the bar being flattened to prevent rotation of the bar on its longitudinal axis, said bar being of the proper length so that it may be detachably mounted on the support by first inserting one end under the lip sufficiently to permit the other end of the bar to clear the spring tongue and then moving the bar longitudinally to engage its last named end under the spring tongue.

WENTWORTH H. SHORTLIDGE.
